PATENTED OCT. 9, 1906.

G. A. KERR.

APPARATUS FOR EXTRACTING TERPENES AND ROSIN.

APPLICATION FILED SEPT. 28, 1905.

UNITED STATES PATENT OFFICE.

GEORGE A. KERR, OF LYNCHBURG, VIRGINIA.

APPARATUS FOR EXTRACTING TERPENES AND ROSIN.

No. 832,863.

Specification of Letters Patent.

Patented Oct. 9, 1906.

Application filed September 28, 1905. Serial No. 280,486.

To all whom it may concern:

Be it known that I, GEORGE A. KERR, of Lynchburg, in the county of Campbell and State of Virginia, have invented certain new and useful Improvements in Apparatus for Extracting Terpenes and Rosin; and I do hereby declare the following to be a full, clear, and exact description of the invention, such as will enable others skilled in the art to which it appertains to make and use the same.

The primary object of this invention is to provide a machine having means whereby the extraction of terpenes and rosin from rosin-bearing woods may be effected during the single passage of wood through the still, the wood being continuously fed in at one point and continuously discharged at another.

A further object is to enable the terpenes to be quickly and effectively extracted in a single and continuous passage thereof through the still.

According to my invention the chips or slivers of pine or other rosin-bearing wood are fed into one end of a still through which they are caused to travel, steam being supplied to only so much of the wood as it can liberate of terpenes, the wood being constantly subjected to a fresh supply of steam. The wood freed of the terpenes passes into an extractor containing an alkaline solution which is kept at such temperature that the wood when discharged by a conveyer from the extractor will be freed from all rosin, which is taken up by the alkaline bath, the latter flowing off through a suitable outlet.

The invention will be hereinafter fully set forth, and particularly pointed out in the claims.

40 In the accompanying drawings, Figure 1 is a vertical longitudinal sectional view. Fig. 2 is a transverse sectional view on line 2 2, Fig. 1.

45 Referring to the drawings, 1 designates the receiving-conveyer, which is shown in the form of an endless screw 2, inclosed by a circular still-casing 3. The conveyer-shaft 4 is hollow and designed to receive at one end steam from an engine or boiler, exhaust-50 steam being preferable. Between the several convolutions of the conveyer, save those directly beneath the charging-hopper 5, the shaft 4 is equipped with outlet-ports 6, through which the steam escapes to the wood 55 confined between such convolutions. The shaft also carries radially-extended arms 7,

which are designed to travel in truly circular planes, so as to agitate or cascade the chips as they are forced forward by the conveyer, and thus insure their being fully acted upon by 60 the steam. Mounted longitudinally above the casing 3 is a receiving-chamber 8, connected with the former by a series of pipes 9, so that the steam charged with terpenes passing from the still-casing 3 will enter 65 receiving-chamber 8, whence it passes to a condenser. (Not shown.) By omitting the outlet-ports from the shaft at the receiving end of the still no steam is liable to escape through the hopper. The wood as it travels 70 through the still is constantly subjected to a fresh supply of steam, and the terpene-laden steam passes directly off instead of having to travel through an extended amount of wood. This is due to the fact that the convolutions 75 of the screw conveyer divide the wood into equal helical portions, and the steam admitted to the spaces defined by the several convolutions contacts with only so much wood 80 as it can free, in part at least, of terpenes.

10 designates a second screw conveyer, preferably below and parallel with the first-mentioned conveyer, its casing 12 being connected with the casing 3 by a conduit 13, so that the wood as it is discharged from casing 3 will fall into casing 12. This second conveyer is constructed similarly to that before described; but the casing wherein it is located is preferably of U shape in cross-section, as shown in Fig. 2. Within this casing is an alkaline bath through which the wood freed of the terpenes is forced to travel. This alkaline bath and the wood are kept at the proper temperature by the steam fed thereto through the conveyer-shaft, which latter has 95 escape-ports 14 formed therein throughout its length. The casing 12 at its discharge end has a trough or chamber 15, the bottom of which is beneath the bottom of the casing, and from this trough extends an outlet-pipe 16, which is located as near the axial center of the conveyer as possible, so as to always maintain the bath at a sufficient depth within the conveyer-casing. The rosin-containing solution flows off through the pipe 16, 100 while the wood as it is discharged from the conveyer falls onto a third conveyer 17, extended diagonally out of the trough, for conveying it away.

In practice the wood in the form of chips or slivers is fed through the hopper into the receiving end of still-casing 3, and being

taken up by the constantly-rotated screw conveyer will be gradually and continuously fed forward through such casing, the supply from the hopper being constant. As the wood is fed along through the casing it is agitated by the radial arms, so that the steam as it escapes into the spaces defined by the several convolutions will act uniformly upon all of the wood. The steam thus carrying off the terpenes will immediately escape through the pipes 9 into the delivery-chamber 8, and as the wood proceeds on its travel through the casing it is continuously agitated and constantly subjected to a fresh supply of steam, with the result that as it reaches the discharge end of the still-casing it will be entirely freed of the terpenes. Thereupon the wood falls through conduit 13 into the casing of the rosin-extractor, through which it will be caused to travel by the endless conveyer being agitated by the radial arms, as in the turpentine-extracting still. The alkaline-bath within the rosin-extractor, as well as the wood, is kept at proper temperature by the steam escaping through the tubular shaft of the conveyer. By the time the wood reaches the discharge end of the extractor all the rosin thereof will have been taken up by the alkaline bath, and the latter will flow off through the outlet 16, while the wood is conveyed away by the conveyer 17.

I claim as my invention—

1. An apparatus of the character herein described, comprising a still or digester, means for extracting terpenes from the wood while in such still, an extractor for receiving the wood from said still, and means for extracting the rosin from the wood while in such extractor.
2. An apparatus of the character herein described, comprising a still or digester, means for extracting terpenes from the wood while in such still, an extractor for receiving the wood from the still, and means for supplying steam to said extractor, which latter is constructed to maintain a rosin-extracting bath therein.
3. An apparatus of the character herein described consisting of a still or digester into which the wood to be treated is continuously introduced at one point and discharged at another, means for continuously conveying the wood between such points, means for supplying steam to the still, an extractor for receiving the wood as it is discharged by the still, means for supplying steam to said extractor, and means in the latter for conveying the wood therethrough, said extractor being constructed to maintain a rosin-extracting bath therein.
4. An apparatus of the character herein described consisting of a still or digester into which the wood to be treated is continuously introduced at one point and discharged at another, means for continuously conveying

the wood through and agitating it in said still, means for supplying steam to the latter, an extractor receiving the discharge from the still, means in said extractor for conveying the wood therethrough, and means for supplying steam to said extractor, the latter being constructed to maintain a rosin-extracting bath therein. 70

5. An apparatus of the character herein described consisting of a still or digester into which the wood to be treated is continuously introduced at one point and discharged at another, means for continuously conveying the wood through and agitating it in said still, means for continuously supplying steam at or about the axis of said still, an extractor receiving the discharge from the still, means in said extractor for conveying the wood therethrough, and means for supplying steam at or about the axis of the extractor, 80 said extractor being constructed to maintain a rosin-extracting bath therein. 85

6. An apparatus of the character herein described consisting of a still or digester into which the wood to be treated is continuously introduced at one end and discharged at the other, means for continuously conveying the wood through such still, means for supplying steam to different points of the still at or about the axial center thereof, means for allowing of the escape of the terpenes-laden steam at different points of the still, an extractor receiving the discharge from the still, means in said extractor for conveying the wood therethrough, and means for supplying steam to said extractor, the latter being constructed to contain a rosin-extracting bath therein. 95

7. The herein-described apparatus comprising a still into which the wood to be treated is introduced into one end and discharged at the other, a terpenes-receiving chamber located above said still and connected thereto at different points, an endless conveyer within said still having a hollow 100 shaft formed with openings, steam being introduced through such shaft and escaping through said connections to said chamber, an extractor, a conduit for conducting the discharge from the still to said extractor, 110 said extractor being designed to contain a rosin-extracting bath, an endless conveyer within said extractor having a hollow shaft formed with openings for the escape of steam supplied through said shaft, a trough at the 115 discharge end of the extractor, a conveyer therein, and an outlet for the rosin-extracting bath. 120

In testimony whereof I have signed this specification in the presence of two subscribing witnesses.
